United States Patent Office

Des. 184,266
Patented Jan. 13, 1959

184,266

PLASTIC SHEET MATERIAL OR SIMILAR ARTICLE

Arno H. Scheiding, Rowayton, Conn., assignor to L. E. Carpenter & Company, Inc., Wharton, N. J., a corporation of New Jersey

Application November 27, 1957, Serial No. 48,689

Term of patent 14 years

(Cl. D87—3)

Fig. 1.

Fig. 2.

Fig. 1 is a plan view of a piece of plastic sheet material embodying the new design; and

Fig. 2 is a sectional view taken along the line II—II of Fig. 1, illustrating the contours of the embossed ridges and grooves in the plastic sheet material.

I claim:

The ornamental design for a plastic sheet material or similar article, substantially as shown.
